United States Patent Office.

JOHN HALE, OF SCRANTON, PENNSYLVANIA.

Letters Patent No. 96,227, dated October 26, 1869.

IMPROVED DRILLING-MACHINE.

The Schedule referred to in these Letters Patent and making part of the same.

To all whom it may concern:

Be it known that I, JOHN HALE, of Scranton, in the county of Luzerne, and in the State of Pennsylvania, have invented certain new and useful Improvements in Drilling-Machine; and do hereby declare that the following is a full, clear, and exact description thereof, reference being had to the accompanying drawings, and to the letters of reference marked thereon.

My invention relates to the kind of drills known as "bow or fiddle-drills;" and consists in a uniform feed, operated by a spiral spring, or its equivalent, and in the application of an extension-bar, whereby holes of considerable length may be drilled.

In order to enable others skilled in the art to which my invention appertains, to make and use the same, I will now proceed to describe its construction and operation, referring to the annexed drawings, which form a part of this specification, and in which—

Figure 1 is a side elevation of my drill; and

Figure 2 is a side view, part in section, of the automatic feeding-device.

A represents a metallic frame, of suitable dimensions, secured to the table.

In the upper ends of the frame A the drill-spindle B has its bearings, being constructed in any of the known and usual ways.

Under the drill-spindle B, in slots on the frame A, runs an extension-bar, C, which may be placed at any point desired, and held by a thumb-screw, D.

The end of the bar C, on the side of the frame

where the drill is placed, is bent upward, and at a point directly opposite the drill a, it is provided with a metal casing, E, extending horizontally outward.

In the casing E is placed a plunger, b, surrounded by a spiral spring, c, and so constructed with a flange or collar inside of the casing, that the spring will press said plunger a certain distance out of the casing toward the drill.

At the outer end of the plunger b, square with the drill, is a face-plate, d.

The work to be drilled being placed, in a suitable manner, against said face-plate, and the plunger pressed into the casing, it will be seen, that as the drill operates, boring the hole the spiral spring c, pressing the plunger, will feed the work straight to the drill, and by the use of the extension-bar C, a hole may be drilled the same length as this bar.

Having thus fully described my invention,

What I claim as new, and desire to secure by Letters Patent, is—

The arrangement of the frame A, the drill-spindle B, extension-bar C, set-screw D, casing E, plunger b, spiral spring c, and face-plate d, all substantially as shown and described.

In testimony that I claim the foregoing, I have hereunto set my hand, this 9th day of March, 1869.

JOHN HALE.
